UNITED STATES PATENT OFFICE.

ALFRED C. GILBERT, OF NORTH HAVEN, CONNECTICUT, ASSIGNOR TO THE A. C. GILBERT COMPANY, OF NEW HAVEN, CONNECTICUT, A CORPORATION OF MARYLAND.

DESIGN FOR A BOWL FOR A FRUIT-JUICE EXTRACTOR.

Application filed February 12, 1929. Serial No. 30,026. Term of patent 14 years.

To all whom it may concern:

Be it known that I, ALFRED C. GILBERT, a citizen of the United States, residing in North Haven, in the county of New Haven, and State of Connecticut, have invented a new, original, and ornamental Design for Bowls for Fruit-Juice Extractors, of which the following is a specification when taken in connection with the accompanying drawing.

Fig. 1 is a side elevational view of a juice extractor bowl, showing my new design;

Fig. 2 is a bottom plan view of the same, and

Fig. 3 is a sectional view on lines 3—3 of Fig. 2.

I claim:

The ornamental design for a bowl for a fruit juice extractor substantially as shown.

ALFRED C. GILBERT.
